ATTACHMENT FOR HEEL-NAILING
MACHINES

Clarence M. De Wolfe, Somerville, Mass., assignor to The B. F. Goodrich Company, New York, N. Y., a corporation of New York

Application October 21, 1942, Serial No. 462,779

6 Claims. (Cl. 1—32)

This invention relates to heel-nailing machines such as are utilized for attaching wooden heels to shoes, and particularly relates to an attachment to be used on and with such machines.

In the manufacture of shoes having wooden heels it is common practice to employ a semi-automatic machine for nailing the wooden heels on the shoes. This machine includes a nail storage portion and means for transferring the nails from storage to a nail receiver so that driving means can be employed for nailing the heels onto the shoe. The nail transferring means, in most machines, includes a moving carrier means for transporting the nails to nailing position in the nail receiver. In order to obtain maximum production per machine the movement of the nail carrier means is usually quite rapid. Because of this rapid movement of the nail carrier means nails are quite often jarred or shaken out of place and, although the waste in nails is not great, it results in incorrectly nailed shoes and sometimes in broken heels. It is an object of this invention to provide an attachment for heel-nailing machines so that the nails may be held positively in position while they are being transported to the nail receiver preparatory to their being driven into a shoe heel.

In practicing my invention with a heel-nailing machine of the type described above, I provide an attachment on the nail carrier means which comprises closure means to completely cover and close off the nail receptacles in the nail carrier means while nails are enclosed within said means. This prevents the nails from being lost in transit. In the more common type of heel-nailing machine which includes a nail hopper as the nail storage portion, a nail receiver, and carrier means comprising a nail carrier block having apertures therein for receiving the nails, I provide elements including closure means normally overlying the apertures in the nail carrier block while the block is travelling from the nail hopper to the nail receiver. There is also provided means for opening the closure means when the nail carrier block is positioned under the nail hopper. The closure means of this invention may conveniently consist of a flat hinged closure plate held in its normally closed position by means of an ordinary spring or similar resilient element. The means for opening the closure means can be a raised and preferably curled portion on the flat closure plate which is engaged by a projection on the nail hopper to push the closure means up and to one side so that it will not interfere with filling the

apertures in the nail carrier block with nails from the nail hopper.

The invention as illustrated by a preferred embodiment will be described in greater detail with reference to the accompanying drawing, of which

Fig. 1 is an elevation of a portion of a heel-nailing machine with the attachment comprising my invention in place thereon, successive positions of the nail carrier block and closure plate being shown in broken lines; and

Fig. 2 is a perspective view of the nail carrier block with the closure means of this invention thereon in partially opened position.

In a typical heel-nailing machine 10 having a rigid framework 11 as illustrated, there is usually provided an anvil 12 against which a shoe heel can be held while nails N are being driven into it. Immediately beneath the anvil 12 there is provided a hammer guide 13 on which the shoe is placed for the nailing operation and within this hammer guide there is provided a nail receiver 14 for holding the nails N in driving position and a vertically acting power-driven hammer 15 (power means not shown) for driving the nails into the shoe. There is also provided a nail hopper 16 for holding a supply of nails and a nail carrier block 17 to carry the nails from the nail hopper 16 to the nail receiver 14 so that the nails may be placed in position to be driven by the power driven hammer 15. In order that the nails will be placed in proper position for driving, the nail hopper 16 feeds the nails head downward into apertures 18 in the nail carrier block 17. When the carrier block is positioned over the nail receiver 14 the nails drop down into the receiver and the carrier block 17 is returned to the hopper for another load of nails. While the carrier block is on its return journey the nails are driven into the shoe by the hammer 15.

As can be seen from the above description, if the nails are jarred from the nail carrier block 17 while it is moving from the nail hopper 16 to the nail receiver 14, there will be an insufficient number of nails delivered to the receiver and some of the shoes will be ruined. In order to prevent such loss I provide an attachment to serve as closure means over the nail carrier block 17 so that the nails will not be jarred from position by the rapid movement of the carrier block from the hopper to the receiver. A typical embodiment of this closure means may conveniently consist of a closure plate 19 attached to the nail carrier block 17 as by means of a screw 20. This closure plate 19 covers the top of the carrier block and has a hinged joint 21 so that it may be raised

from the top of the carrier block when the block is under the nail hopper 16. In order to hold the closure means in its normally closed position there is provided a spring or similar resilient means 22 (Fig. 2) at the hinged joint 21 of the closure plate. The closure plate is also provided with a raised, curled portion 23 on the end opposite the hinged edge and on the side next the hopper when the carrier block 17 is traveling from the nail receiver to the hopper.

In operating a heel-nailing machine provided with the new attachment of this invention, the nail carrier block 17 is caused to move from the nail hopper 16, to the nail receiver 14, back to the nail hopper, and so on, by reciprocating motion set up as by means of a rack 24 and driving pinion (not shown). As the nail carrier block 17 is pulled under the nail hopper 16 to pick up a supply of nails, the raised, curled portion 23 of the closure plate 19 engages a projection 25 provided on the nail hopper. This raises the closure plate from over the top of the carrier block 17 and permits nails to be fed into apertures 18 in the carrier block. When the carrier block is pushed along its path toward its position over the nail receiver 14 the spring 22 on the hinged edge 21 of the closure plate forces the plate in closed position over the carrier block and holds it there. The nails N are deposited in the nail receiver over the power-driven hammer 15 and the nail carrier block is returned for another load of nails. Then the hammer 15 drives the nails home in the heel of a shoe that is placed in position in the machine. As can be seen the closure plate of this invention is in closed position over the carrier block at all times except when the block is in its position under the nail hopper to receive its load of nails and any possibility of accidental loss of the nails from the carrier block is completely eliminated.

Having described my invention as embodied in a preferred device, it is my intention that the invention be construed broadly within the spirit and scope of the invention as set out in the following claims.

I claim:

1. In a nailing machine of the character described including a nail hopper, a nail receiver, and a nail carrier block arranged for reciprocating travel between the hopper and the receiver and having apertures therein, hinged closure means normally overlying the apertures in the nail carrier block while the block is travelling from the nail hopper to the nail receiver, and means for hingedly opening the said closure means when the nail carrier block is positioned under the nail hopper.

2. In a nailing machine of the character de-

scribed including a nail hopper, a nail receiver, and a nail carrier block arranged for reciprocating travel between the hopper and the receiver and having apertures therein, elements including 5 closure means normally overlying the apertures in the nail carrier block while the block is travelling from the nail hopper to the nail receiver, and means for opening the said closure means when the nail carrier block is positioned under the 10 nail hopper, said closure means comprising a hinged closure plate, and means tending resiliently to hold the plate in its normally closed position over the apertures in the nail carrier.

3. In a nailing machine of the general character described including nail supplying means, nail receiving means and travelling means for carrying nails from the supplying means to the receiving means, the combination with the aforesaid means of a cover plate for retaining nails in 15 the nail carrying means during its travel, and means for lifting the cover plate from the nail carrying means to expose the nail carrying means to the nail supplying means.

4. In a nailing machine of the general character described including nail supplying means, nail receiving means and travelling means for carrying nails from the supplying means to the receiving means, the combination with the aforesaid means of a cover plate for retaining nails in 20 the nail carrying means during its travel, and means for lifting the cover plate from the nail carrying means to expose the nail carrying means to the nail supplying means.

5. In a nailing machine of the general character described including nail supplying means, nail receiving means and travelling means for carrying nails from the supplying means to the receiving means, the combination with the aforesaid means of a cover plate for retaining nails in 25 the nail carrying means during its travel, and cam means for raising the cover plate from the top of the nail carrying means at the nail supplying means.

30 4. In a nailing machine of the general character described including nail supplying means, nail receiving means and travelling means for carrying nails from the supplying means to the receiving means, the combination with the aforesaid means of a cover plate for retaining nails in the nail carrying means during its travel, and cam means for raising the cover plate from the top of the nail carrying means at the nail supplying means.

40 5. In a nailing machine of the general character described including nail supplying means, nail receiving means and travelling means for carrying nails from the supplying means to the receiving means, the combination with the aforesaid means of a cover plate for retaining nails in 45 the nail carrying means during its travel, said cover plate having a projecting portion adapted to cooperate in a cam-like fashion with another portion of the structure to effect upward movement of the cover plate from the top of the nail carrying means at the nail supplying means.

6. In a nailing machine of the general character described including nail supplying means, nail receiving means, and travelling means for carrying nails from the supplying means to the 50 receiving means, the combination with the aforesaid means of a pivotally mounted cover for retaining nails in the nail carrying means during its travel, and means for causing upward pivotal movement of the cover plate to expose the nail carrying means as it approaches the nail supplying means.

CLARENCE M. DE WOLFE.
